[57] CLAIM

The ornamental design for a hose assembly crimping machine, substantially as shown and described.

DESCRIPTION

FIG. 1 is a perspective view of a hose assembly crimping machine embodying my new design; the broken line showing of the stand is for illustrative purposes only; FIG. 2 is a front elevational view thereof, disposed in a vertical position;

FIG. 3 is a side elevational view of FIG. 2;

FIG. 4 is a top plan view of FIG. 2;

FIG. 5 is a bottom plan view of FIG. 2.
